UNITED STATES PATENT OFFICE.

PAUL HALLOT, OF VINCENNES, FRANCE.

RAILWAY-BRAKE.

SPECIFICATION forming part of Letters Patent No. 730,115, dated June 2, 1903.

Application filed November 5, 1902. Serial No. 130,198. (No model.)

To all whom it may concern:

Be it known that I, PAUL HALLOT, a citizen of France, residing at Vincennes, France, have invented certain new and useful Improvements in Railway-Brakes, of which the following is a specification.

This invention relates to certain improvements in the brakes described in the specifications of my prior patents; and it has for its object to simplify the construction thereof in such a manner as to render them applicable to brakes of all other systems without having to alter the arrangement of such other systems.

In order that the invention may be readily understood, I will describe the same fully with reference to the annexed drawings, in which—

Figure 1 is a transverse section of the simplified arrangement of brake combined with the centrifugal governor or regulator shown in section, taken on the axial line of the wheel-axle. Fig. 2 is a section of the said governor, taken on the line A B of Fig. 1. Fig. 3 is an elevation of a modified form of this governor. Fig. 4 is a section of the same, taken on the line C D of Fig. 3. Fig. 5 shows a further modification. Figs. 6 and 7 show various manners of applying the automatic governor to compressed-air brakes of all kinds. Fig. 8 shows the application of the said governor to vacuum-brakes, and Fig. 9 illustrates means for adjusting or varying the power of the brake.

In my prior construction the brake is actuated by means of a drum *a*, carried upon one of the axles of the vehicle and over which passes a cable *b*, connected to the brake-gear. The said drum receives motion from a piston *c*, worked either by compressed air or by vacuum. At the moment of braking a centrifugal apparatus is brought into action and so increases the pressure of the brake-blocks for a determinate amount which automatically disappears directly the rotation of the wheel tends to stop.

The present invention has for its object to introduce certain improvements into brakes of this kind. The roller or pulley of the drum is now replaced by a bevel-pulley *a*, carried by the axle and adapted to be moved longitudinally thereon; so as to be brought into

contact with a friction-cone *d*, (or clutch,) keyed on the axle or on any shaft connected therewith. The rod *c* of the controlling-piston is connected by a bell-crank lever *e* to a rod *f*, which through the medium of the spring *g* causes the lever *i* (engaging in a groove *j* in the drum *a*) to pivot about the axis *h*. The multiplying apparatus is brought into action by the engineman effecting a further lowering of pressure below the piston *c*. The increase in the upward stroke of the said piston compresses the intermediate spring *g* and pulls the operating-lever *k* over to the right by means of the lock-nut *m*, notwithstanding the opposition of the spring *n*.

As shown in Fig. 1, the initial motion of the governor is no longer derived from the wheel-tire, but from the axle, so as to obtain a reduced rotary speed and consequently less wear of the frictional surfaces, although the principle of the automatic working remains the same. In this instance the power is obtained by bringing the bevel-pulley *o* into contact with an intermediate pulley *p*, adapted to participate in the rotation of the axle by centrifugal force only. To this end the friction-cone *d* (keyed on the axle) is cast with a series of partitions *q*, (see Fig. 2,) so as to form compartments in which are loosely placed metal masses *r* of, say, iron or lead. The intermediate pulley *p* is turned on its inner periphery, so as to allow it to fit with a certain amount of play over all these masses.

When at work, the said masses *r* by the action of centrifugal force press against the internal periphery of the pulley *p*, and thus cause the latter to be positively rotated therewith. If, therefore, the pulley *o*, on which is wound the cable *s*, whose action is added to that of the cable *b*, be brought into contact with the pulley *p* while the axle is revolving, the said pulley *o* will be driven; but directly the speed of rotation of the masses *r* becomes lower than the force of the resistance opposed by the cable *s* the connection between the intermediate pulley *p* and these masses will partially cease, which will cause an equal reduction in the power derived from the action of the drum and will therefore automatically regulate the skidding pressure. This system of regulation offers the following advantages 95

(a,) very slight friction, (b,) the action of the drum is not derived from the wheel-tire, (c,) the action of the drum is not derived from the wheel-tire, (d,) the action of the drum is not derived from the wheel-tire, (e,) the action of the drum is not derived from the wheel-tire, (f,) the action of the drum is not derived from the wheel-tire, (g,) the action of the drum is not derived from the wheel-tire, (h,) the action of the drum is not derived from the wheel-tire, (i,) the action of the drum is not derived from the wheel-tire, (j,) the action of the drum is not derived from the wheel-tire, (k,) the action of the drum is not derived from the wheel-tire, (l,) the action of the drum is not derived from the wheel-tire, (m,) the action of the drum is not derived from the wheel-tire, (n,) the action of the drum is not derived from the wheel-tire, (o,) the action of the drum is not derived from the wheel-tire, (p,) the action of the drum is not derived from the wheel-tire, (q,) the action of the drum is not derived from the wheel-tire, (r,) the action of the drum is not derived from the wheel-tire, (s,) the action of the drum is not derived from the wheel-tire, (t,) the action of the drum is not derived from the wheel-tire, (u,) the action of the drum is not derived from the wheel-tire, (v,) the action of the drum is not derived from the wheel-tire, (w,) the action of the drum is not derived from the wheel-tire, (x,) the action of the drum is not derived from the wheel-tire, (y,) the action of the drum is not derived from the wheel-tire, (z,) the action of the drum is not derived from the wheel-tire.

tion between the rubbing-surfaces, (about one hundred and fifty grams per square centimeter;) (b,) very regular working at all speeds; (c,) no necessity for lubrication; (d,) very great power with reduced bulk. This power may be increased in a very appreciable ratio, while avoiding wear of the metal masses. To this end a steel band t , Fig. 2, in the form of a ribbon may be interposed between the masses r and the inner periphery of the intermediate pulley p . The circumferential development of this steel band is less than that of the pulley, and the two ends of the said band are riveted to two steel driving-blocks u v , capable of being readily displaced in two corresponding recesses cast in two adjacent masses r . Whatever may be the direction of rotation of the masses, one of the blocks—for example, u —will be arrested by the common partition w , the other extremity tending, on the contrary, to recede therefrom, and this all the more as the effect of the centrifugal force increases. Figs. 3 and 4 show a more powerful arrangement, which is obtained by giving two turns to the band t and by causing it to act directly on the pulley p . To this end the said pulley is formed with two abutments or stops x y , cast thereon. The band t is composed of two lateral ribbons 1 and 2, terminating in axes 3 and 4, adapted to bear against the abutment or stop x when rotation takes place in the direction of the arrow. These two ribbons are coupled by a common axis 7 to an intermediate ribbon 5, which terminates at its other end in an axis 6. The masses when revolving tend to carry the ribbon with them, and said ribbon, through its axes 3 and 4, drives the pulley p with a force equal to the centrifugal throw of the masses r . Fig. 5 shows a detailed arrangement wherein the interior periphery of the intermediate pulley p is provided either with grooves or with slightly-projecting ribs designed to facilitate the driving of this pulley by centrifugal force. According to this particular arrangement iron balls 7 are loosely arranged in superposed layers above the masses r . It is to be remarked, moreover, that the various arrangements of this government do not in any wise modify the working of the devices described in my previous specifications herein referred to and which serve to increase and regulate the pressure of brakes of all systems. The force transmitted by the cable s on the drum o may, in fact, be utilized in very different ways without departing from the principle of the present invention. In particular the special action of this government may be utilized to double the power of all compressed-air brakes and to render such brake action proportional to the load on the axles without introducing any modification into existing brakes. To this end the friction-cone d , Fig. 1, keyed on the axle, is reduced to a simple box d , Fig. 7. The cable s directly actuates a suitably-arranged reinforcing connecting-rod 8, Fig. 8,

connected with the existing brake-gear by a connecting-band, such as 9.

10 represents the piston-rod of the usual 70 brake-cylinder.

For goods-trucks of heavy tonnage the arrangement shown in Fig. 6 will be found very advantageous. The cable s passes over a pulley 11 and its free end is secured to one 75 end of a rocking lever 12, pivoting about its center, and the other end of which is coupled to the axis of the pulley 11. The connecting-band 9 is connected to the rod 8 by any suitable means. Coupling-holes provided in 80 the rod 8 permit the constant force of the cable s to produce on the connecting-band 9, and hence on the brake-gear a variable force, according to the load carried by the vehicle, so that the braking force is in constant ratio 85 with the load on the axles. If it be desired to diminish the tension of the cable s , it is only necessary to provide a tackle. Fig. 8 shows the same arrangement applied to an ordinary passenger-coach provided with a 90 vacuum-brake. As the load is appreciably constant and by no means high, (five to six, French tons,) the cable s is directly attached to the end of the connecting-rod 8, and the connecting-band 9 is permanently connected 95 to this rod.

Fig. 9 shows an additional arrangement whereby the power of any brake can be strictly regulated whenever an excess of force can be economically availed of. For 100 this purpose the spring 13, which serves to draw the connecting-rod i backward, is such as to set up a determined resistance (for instance, twenty-five per cent. of the weight-brakes) in addition to the force necessary to 105 insure the disengagement of the cone a . This regulating-spring is secured to a screw-rod 14, adapted to advance without turning when the adjusting-nut 15 is operated. The end of this screw-rod carries an index 16, which 110 is placed opposite the division 80 of a graduated plate 17, suitably fixed to the under carriage of the coach after the brake has been regulated. During the testing of the brakes this force of eighty per cent. of the 115 weight braked is preferably obtained by suitably adjusting the stop-screw 18, the effect of which is to vary the initial position of the piston c in the cylinder, and hence the value of the expansion. The brakes having been 120 thus adjusted, it is sufficient, if it be subsequently desired to alter their power for use with another system, to suitably operate the nut 15 to bring the index 16 opposite the division representing the desired force. 125

It will be obvious that the friction-cone described in this specification instead of being mounted on the car-axle may be arranged on any shaft rotated by the car-axle or by the movement of the car, and therefore when in 130 the following claims I refer to the "car-axle" I desire said term to also include a shaft operated by the car-axle or by the movement of the car.

Having now particularly described and ascertained the nature of my said invention and in what manner the same is to be performed, I declare that what I claim is—

- 5 1. The combination with the car-axle, of a series of compartments arranged around said axle, each of said compartments containing a mass adapted to be displaced by centrifugal force, a pulley surrounding said compartments and adapted to be engaged by said masses, and means for operating the car-brakes by the movement of said pulley.
- 10 2. The combination with the car-axle, of a series of compartments arranged around said axle, each containing a mass adapted to be displaced by centrifugal force, a pulley surrounding said compartments and adapted to be engaged by said masses, the outer surface of said pulley being coned, a cone-pulley mounted on said car-axle, means for operating the car-brakes by the movement of said cone-pulley and means for throwing said cone-pulley into engagement with the coned outer surface of said first-mentioned pulley.
- 15 3. The combination with a car-axle, a cone-pulley mounted on said car-axle and rotating therewith, a second cone-pulley loosely mounted on said car-axle, means for operating the car-brakes by the movement of said second cone-pulley, a series of compartments arranged around said car-axle, each containing a mass adapted to be displaced by centrifugal force, a pulley surrounding said compartments, the outer surface of said pulley being coned, a third cone-pulley mounted on
- 20 said car-axle, means for operating the car-brakes by the movement of said third cone-pulley and means for simultaneously throwing said second cone-pulley into engagement
- 25 with said first-mentioned cone-pulley and
- 30
- 35
- 40

said third cone-pulley into engagement with the coned outer surface of the pulley which surrounds said compartments.

4. The combination with a car-axle, of a cone-pulley mounted thereon and rotating therewith, a second cone-pulley loosely mounted on said shaft, said second cone-pulley having a contracted sleeve portion, means for operating the car-brakes by the movement of said second cone-pulley, a plurality of compartments arranged around said car-axle, each containing a mass adapted to be displaced by centrifugal force, a pulley surrounding said compartments adapted to be engaged by said masses, the outer surface of said pulley being coned, a third cone-pulley loosely mounted on said car-axle, said third cone-pulley having a contracted sleeve portion, means for operating the car-brakes by the movement of said third cone-pulley, a forked lever engaging the contracted sleeve portion of said second cone-pulley, a second forked lever engaging the contracted sleeve portion of said third cone-pulley, a piston controlled by the engineer, and means operated by said piston for actuating said first and second levers to throw said second cone-pulley into engagement with said first-mentioned cone-pulley and said third cone-pulley into engagement with the outer coned surface of the pulley which surrounds said compartments.

In testimony whereof I have hereunto set my hand in presence of two subscribing witnesses.

PAUL HALLOT.
